COKE OVEN

Filed May 3, 1929

UNITED STATES PATENT OFFICE

PAUL ETIENNE VERPEAUX, OF BRUSSELS, BELGIUM, ASSIGNOR TO UNION CHIMIQUE BELGE, SOCIETE ANONYME, OF BRUSSELS, BELGIUM

COKE OVEN

Application filed May 3, 1929; Serial No. 360,102, and in Belgium April 3, 1929.

This invention relates to coke ovens.

Horizontal coke ovens with vertical flues are known in which the heating flues of the sidewalls receive the gas through a certain number of chambers, each of which is fed in a well regulated manner by a special distributor. In ovens made of silicious and aluminous bricks it is of importance that the gas should be burned at the lower part of the heating flues with an excess of air so as to avoid a fusing of the bricks.

Modern ovens made of silicious bricks make it possible to increase the temperature in the heating flues appreciably, and under these conditions it has now been found useful to effect the combustion of the gas in the flues, in a different manner. As the height of these ovens is greater, it is advantageous to effect the combustion of the gas admitted into the heating flues, in a progressive manner. At the lower part of these flues, the mixture of gas and air does not contain an excess of air, but rather an excess of gas, and this excess of gas is burned at various levels of the heating flues by successive inlets of air so as finally to give products of combustion containing only a small percentage of non-combined oxygen.

The object of the present invention is a special arrangement of coke ovens which enables to effect in a rational manner the successive combustion of the gas in the heating flues of modern ovens made of silicious bricks.

The admission of gas into the various heating flues will be still regulated by means of the gas chambers above referred to. In the walls situated along the individual regenerators of the ovens, air expansion chambers are placed by means of which the primary combustion of the gas at the bottom part of the heating flues can be followed by several successive combustions effected in a well regulated manner at various levels of the heating flues of the sidewalls, and each of these air expansion chambers is connected on the one side with several header flues opening at the desired level of the heating flues, and on the other side with a distributor connected with a pipe containing air under pressure.

To each gas chamber corresponds a certain number of air expansion chambers, which number is equal to the number of successive combustions to take place after the primary combustion at the lower part of the heating flues. The air admissions to the various air expansion chambers are opened or closed periodically in a manner similar to that of the gas admissions into the gas chambers.

The present improvements made in the method of distributing air to the heating flues enable to effect at each moment a regulation as perfect as possible, of the temperature at various levels of the sidewall.

The accompanying drawing shows, by way of example, one mode of carrying the invention into effect.

Figure 1 is a longitudinal vertical section made along the line A—B of Figure 2;

Figure 2 is a horizontal section made along the line C—D of Figure 1;

Figure 3 is a vertical cross-section, the left hand side of which is made along the line E—F of Figure 2, and the right hand side of which is made along the line G—H of Figure 2.

In the drawing, flues 2 in the sidewalls of ovens 1 receive the gas through openings 3 connected with gas chambers 4, each of which is fed by a special distributor 10.

In the description given hereinafter, the numerals without a dash are used for the various parts of the construction which are situated on the left hand side of the oven, and the numerals with a dash are used for the corresponding parts on the right hand side of the oven.

Each sidewall contains a certain number of vertical heating flues 2 and 2' which communicate through gas inlets 3 and 3' with four gas chambers 4 and 4' situated underneath, and receiving coke oven gas through pipes 10 and 10' provided with diaphragms.

One half of the sidewall receives the gas through a pipe 10, and the other half receives it through a pipe 10'. The heating flues 2 and 2' are connected at their lower part through connections 8 and 8' with the individual regenerators 6 and 6' situated below the ovens and between which is placed a par-

tion 7 coinciding with the axis of the battery. The various regenerators 6 and 6' communicate at their lower part with longitudinal regenerators 9 and 9' connected with the chimney by means of flues 12 and 12'. Underneath the gas chambers 4 and 4', the sidewalls are prolonged by walls 13 and 13' which act as separation walls between the various regenerators 6 and 6' of two successive ovens.

In each separation wall 13 and 13', that is for each half part of the sidewall, are placed two series of four air expansion chambers, one of the series being shown at 14, and the other at 15. The four air expansion chambers of each series correspond with the four gas chambers 4 or 4' of one or the other of the halves of the corresponding sidewall. Each of the chambers 14 or 14' is connected on the one side through a conduit 16 or 16' with an air distributor 18 or 18', and on the other side through several header flues 25 or 25' with the upper part 24 or 24' of the sidewalls. Each of the chambers 15 or 15' is connected on the one side through a conduit 17 or 17' with an air distributor 19 or 19', and on the other side through several header flues 23 or 23' with a certain level 22 or 22' of the heating flues. Each pair of distributors 18-19 and 18'-19' is branched on an air delivery pipe 20 or 20' in which the air is maintained at a certain pressure.

Let us suppose that the cocks 21 connecting the gas delivery pipe 11 with the gas chambers 4 are open, and that the cocks 21 connecting the gas pipe 11' with the gas chamber 4' are closed. The reversing valve of the battery is placed in such a manner as to let the air arrive through the flues 12 into the longitudinal regenerators 9, from which it is distributed into the various individual regenerators 6, and in such a manner as to evacuate the products of combustion through the flues 12'. At the upper part of each individual regenerator the hot air enters through the openings 8 into the heating flues 2 where it meets the gas rising from the gas chambers 4 through the openings 3. The proportion of gas and the first admission of air is so chosen as to give an incomplete combustion of the gas. The flame rises in each heating flue 2 and it meets at a certain level a secondary admission of air which flows out through the opening 22. The two openings 22 of two adjacent flues 2 are branched on a single header flue 23, the latter descending in the wall 13 which acts as a separation wall between two distinct regenerators 6, and being connected at its lower part with one of the air expansion chambers 15 which is connected by a tube 17 to the distributor 19. The regulating member provided on each tube 17 makes it possible to adjust the amount of air admitted into the correspond-

ing air expansion chamber 15 at will, and thus to adjust exactly the flow of secondary air admissions corresponding to one and the same admission of gas through one or the other of the gas chambers 4.

The flame which has received the said secondary admission of air at 22 in each heating flue 2, continues its combustion at the upper part of the flue, and it enters into the horizontal collecting flue 5, where it receives a third admission of air escaping through an opening 24. This opening 24 is the outlet of a header flue 25 which descends also in the separation wall 13 and which is connected also with one of the air expansion chambers 14, the lower part of which is connected by a tube 16 to the distributor 18. The regulating member provided on each tube 16 makes it possible to adjust the amount of air admitted to the corresponding air expansion chamber 14 at will, and thus to adjust exactly the flow of the third admission of air for effecting a perfect combustion of the combustible elements arriving through each flue 2 into the horizontal collecting flue 5.

The collecting flue 5 is connected with a collecting flue 5' which distributes the products of combustion into the heating flues 2' of the other half of the sidewall. These products of combustion are collected inside the regenerator 6' of the corresponding oven, where they give up the major portion of their heat. At the lower part of the various regenerators 6' the products of combustion are collected in the longitudinal regenerators 9' and evacuated to the chimney through flues 12'.

At the next reversion of the gaseous current, the reversing valve of the battery is placed in such a manner as to let the air arrive through the flues 12 into the longitudinal regenerators 9' from which it is distributed into the various individual regenerators 6' and in such a manner as to evacuate the products of combustion through the flues 12. The cocks 21 connecting the gas pipe 11 with the gas chambers 4 will be closed and the cocks 21' connecting the gas pipe 11' with the gas chambers 4' will be open. The admissions of air from the pipe 20 to the distributors 18 and 19 will be closed, and those from the pipe 20' to the distributors 18' and 19' will be open. The heating of the right-hand side of the sidewall is effected in a manner similar to that indicated for the left hand side of the sidewall.

The improvements described apply to ovens heated with lean gas and to ovens heated simultaneously with rich and with lean gas.

I claim:

1. A series of alternate horizontal coking chambers and heating walls therefor arranged side by side in a row, each of said

heating walls comprising vertical combustion flues separated by partition walls, gas chambers communicably connected with the flues and located under the said combustion flues and partition walls, air expansion chambers located underneath the said gas chambers, regenerators communicating with the combustion flues and alternating with the air expansion chambers along said series, auxiliary flues positioned in the partition walls and opening into the combustion flues at different levels, said air expansion chambers being communicably connected with said auxiliary flues extending in the partition walls, an air supply conduit, and a gas distributor communicably connected with said air supply conduit and said air expansion chambers.

2. A series of alternate horizontal coking chambers and heating walls therefor arranged side by side in a row, each of said heating walls comprising vertical combustion flues separated by partition walls, and comprising gas chambers in communication with the combustion flues at the lower parts thereof and located under the said flues and partition walls, auxiliary flues in said partition walls opening into said combustion flues at two different levels above the communications of said gas chambers with said combustion flues, two superposed series of air expansion chambers located underneath the combustion flues and communicating therewith through said auxiliary flues at said two different levels respectively, regenerators communicably connected with the combustion flues and alternating with the air expansion chambers along said row, a gas distributor, and an air supply conduit in communicable connection therewith, the said air expansion chambers being in communication with the said distributor.

3. A series of alternate horizontal coking chambers and heating walls arranged side by side in a row, each of the said heating walls comprising vertical combustion flues separated by partition walls, gas chambers located under the combustion flues and partition walls, and communicating with said combustion flues at the lower parts thereof, auxiliary flues in said partition walls opening into said combustion flues at two different levels above the communications of said gas chambers with said combustion flues, two superposed series of air expansion chambers located underneath the gas chambers and communicating with said combustion flues through said auxiliary flues at said two different levels respectively, regenerators communicably connected with the combustion flues, and alternating with the air expansion chambers along said row, a gas distributor, and an air supply conduit communicably connected with the said distributor, the said air

expansion chambers being in communicable connection with the distributor, and means for controlling the admission of air into the said expansion chambers.
